UNITED STATES PATENT OFFICE.

WILLIAM R. FOX, OF GRAND RAPIDS, MICHIGAN.

PENCIL-SHARPENER.

1,257,690.

Specification of Letters Patent. Patented Feb. 26, 1918.

Application filed October 31, 1913. Serial No. 798,502.

To all whom it may concern:

Be it known that I, WILLIAM R. Fox, a citizen of the United States, residing at Grand Rapids, Michigan, have invented certain new and useful Improvements in Pencil-Sharpener, of which the following is a specification.

This invention relates to improvements in pencil sharpeners.

10 The objects of the invention are:

First, to provide a pencil sharpener which will give a pencil a perfectly smooth and uniform point and in which the pencil will be so supported during sharpening as to be 15 free from all torsional strain.

Second, to provide a pencil sharpener so constructed that it can be operated directly by an electric motor.

Third, to provide a device of this type in 20 which the dust is automatically thrown out of the machine into a suitable receptacle.

Further objects, and objects relating to details and economies of construction and operation will definitely appear from the detailed description to follow.

I accomplish the objects of my invention by the devices and means described in the following specification. The invention is further described and pointed out in the 30 claims.

A structure constituting a preferred embodiment of my invention is clearly illustrated in the drawing forming a part of this specification, in which:

35 Figure I is a perspective view of the device.

Fig. II is a perspective view with the motor and sharpening disks removed from the same.

40 Fig. III is a sectional view on the line 3—3 of Fig. IV, showing the pencil in position against the face of one of the disks.

Fig. IV is a sectional view on the irregular line 4—4 of Fig. III, showing the pencil 45 in sharpening position.

Fig. V is a sectional view on the line 5—5 of Fig. III, showing in detail the anchoring means for the pencil supporting member.

Fig. VI is a detail view of the parts shown 50 in the left hand portion of Fig. IV, the pencil and the casing being removed.

In the drawing, the sectional views are taken looking in the direction of the little arrows at the ends of the section lines and 55 similar numerals refer to similar parts throughout the several views.

Considering the numbered parts of the drawing, the numeral 1 designates the base plate, to which is secured an electric motor 2 of any suitable type. This is provided 60 with binding posts 3, at which connection is made with the source of electric current. 4 is the motor shaft. Secured to the base by screws 8 is the block 7 having a curved seat to which a casing is fastened by means of 65 the screws 9. This casing comprises the disks 5 which are secured to and spaced apart by the circular strip 6 which is fastened in the seat of the block 7 heretofore mentioned. Openings are provided in the 70 disks 5 to accommodate the shaft 4 of the motor.

Secured to the shaft 4 is the collar 12 to which are secured the disks 10 and 11 which may be of emery, or of other material, or 75 may be of metal covered with sheets of abrasive material. These disks are thinner at the periphery than at the center and are frustum shaped. They are so placed together that a V-shaped space is left between their peripheries. 13 and 13' are the beveled faces of the respective disks, which form this V-shaped space, and said faces are gently curved outwardly.

Block 14 is secured in the seat 15 on the 85 base. This block is provided with an upright arm and a horizontally extending arm. The horizontally extending arm is forked and is held in position in the seat by means of the bolt 17. The pin 18 acts as a stop to 90 limit the movement of the block on the base. To the upright part of block 14 arm 19 is secured by means of screw 20. This arm has the laterally extending bracket 21 which supports the pencil in sharpening position 95 and is provided with an upstanding lug 22 which prevents the insertion of the pencil beyond the lug. This bracket is made narrower than the distance between the disks except at the end near lug 22, in order to 100 provide a space on each side through which the grinding dust will pass. This is clearly shown in Fig. VI. Arm 19 is provided with rods 23, upon which is slidably mounted the pencil supporting member 24. The numeral 105 25 designates the pencil to be sharpened, which is laid in the V-shaped notches of the pencil supporting members and is held in place by means of the spring 26 fastened to the arm 19 at 27.

Block 28 is secured in seat 15 of the base 110 by means of the screw 29. This block has

a conical shaped opening through which the dust passes out of the machine. An alining opening is provided in the edge 6 of the casting. The edge of the opening in block 28 is 5 provided with a bead 31 by which the edges of a dust bag 32 are secured to the block. From the top of block 28 the lug 33 projects through the opening in the strip 6 and carries thereon a V-shaped guard member 34 10 secured by the screw 35. This guard member is disposed in the space between the two disks and prevents any dust being carried past the opening.

From the description of the parts above 15 given the operation of the structure will be very readily understood. The pencil to be sharpened is placed on the supporting members 24 and 19 and the end thereof is inserted between the edges of the rapidly revolving disks. If it is desired to give the pencil a conical point, it is rotated by hand while it is being sharpened so as to enable the disks of abrasive material to act on all 20 sides of the pencil. If, however, it is desired 25 to give it a wedge point, often desired by draftsmen, it is not rotated but merely pushed in in different positions. Lug 22 engages the end of the pencil and limits the amount to which it can be inserted. This 30 prevents the pencil being worn away by inserting it beyond the V-shaped space between the disks. The location of the lug 22 with reference to the disks and hence the fineness of the point which is given to the 35 pencil is regulated by shifting the block 14 in the slot 15. The dust resulting from the sharpening of the pencil is carried down beside the bracket and around the bottom of the casing and thrown out through the opening 40 30 by means of centrifugal force. Guard arm 34 which is disposed in the V-shaped space between the disks prevents any of the dust being carried up past the opening 30.

It is not necessary that the shaft be rotated 45 by means of an electric motor although this is highly desirable as giving a very rapid rotation. Any other means either mechanical or manual may be used to rotate the shaft.

I have here shown a form of pencil supporting member in which the pencil is rotated by hand. I am aware that pencil supporting members are known in which the pencil is mechanically rotated by means of a 50 driving connection with the operating shaft. Any of these forms of pencil holders may be used in connection with my device. However, the form of holder which I have here shown and described possesses particular advantages and I desire to claim it specifically. 55 I am aware that the particular arrangement of parts I have here shown is susceptible of considerable variation. I therefore do not wish to be restricted to this particular embodiment of my invention, but desire to 60

claim the same broadly. However, the particular embodiment which I have shown is especially effective, and I desire to claim the same specifically as well as broadly, as indicated by the appended claims.

Having thus described my invention, what I claim as new and desire to secure by Letters Patent is:

1. In a device of the class described, the combination of a base, a shaft rotatably mounted thereon, means for rotating said shaft, a pair of sharpening disks secured to said shaft and rotating therewith, said disks being frustum shaped and having a V-shaped space between their peripheries, a pencil supporting member adjustably secured to said base and having an arm extending into the space between said disks and provided at its end with a stop lug, a block secured to the base and having an opening, a suitable dust receiving receptacle communicating with said opening, and a guard arm carried by the top of said block and disposed in the space between said disks, all coacting substantially as described for the purpose specified.

2. In a device of the class described, the combination of a base, a shaft rotatably mounted thereon, means for rotating said shaft, a pair of sharpening disks secured to said shaft and rotating therewith, said disks being frustum shaped and having a V-shaped space between their peripheries, means for supporting a pencil between said disks, a block secured to the base and having an opening, a suitable dust receiving receptacle communicating with said opening, and a guard arm secured to the top of said block and disposed in the space between said disks, all coacting substantially as described for the purpose specified.

3. In a device of the class described, the combination of a base, a shaft rotatably mounted thereon, means for rotating said shaft, a pair of sharpening disks secured to said shaft and rotating therewith, said disks being frustum shaped and having a V-shaped space between their peripheries, means for supporting a pencil between said disks, means for supporting a dust receiving receptacle near the edges of said disks and a guard arm disposed in the space between said disks, all coacting substantially as described for the purpose specified.

4. In a device of the class described, the combination of a base, a shaft rotatably mounted thereon, means for rotating said shaft, a sharpening disk secured to said shaft and rotating therewith, and pencil supporting means comprising a pencil support adjustably secured to the base and extending vertically therefrom, a pencil receiving notch in the end of said support, a spring secured to said pencil support and adapted to pass over the pencil to hold it resiliently in

said notch, horizontal rods extending laterally from said support, a second pencil supporting member slidably carried by said rods and having a notch in alinement with said 5 first named notch, an arm extending laterally from said first named pencil support, and a stop lug on said arm, all coacting substantially as described for the purpose specified.

10 5. In a device of the class described, the combination of a base provided with a groove extending transversely thereof, a shaft rotatably mounted on said base, a pair of sharpening disks secured to said shaft and 15 rotating therewith, a casing surrounding said sharpening disks, openings provided in the side wall of said casing on opposite sides thereof, a pencil support provided with a pencil supporting arm extending laterally 20 between said sharpening disks, said pencil support being provided with a slotted base seated in said groove, a bolt threaded into the base of said groove and passing through the slot in the base of said pencil support, 25 the head of said bolt engaging the base of said pencil support whereby the latter is held in adjusted position, a pin projecting into the groove of said base to limit the inward movement of the pencil support, a block seated in the groove in said base opposite the pencil support and provided with a guard arm projecting through the opening in the casing between the sharpening disks, said block being provided with a funnel shaped 30 mouth in line with the opening in the casing, said mouth being provided with a bead to

which a suitable dust receiving receptacle may be attached, all coacting substantially as described for the purpose specified.

6. In a device of the class described, the 40 combination of a base, a shaft rotatably mounted thereon, means for rotating said shaft, a pair of grinding disks with beveled faces disposed toward each other, a pencil support extending between said disks, a casing 45 surrounding said grinding disks and provided with an opening communicating with a suitable dust receptacle, and a guard arm extending between said disks and adapted to deflect the dust through said opening 50 into said dust receptacle.

7. In a pencil sharpener, the combination with a support, of a pair of grinding disks with beveled faces disposed toward each other, means for rotating said disks in the 55 same direction, a pencil supporting member extending between said disks, a guard arm extending between said disks, and a casing surrounding said disks and provided with an opening therein adapted to communicate 60 with a suitable dust receiving receptacle, said guard arm serving to deflect the dust from between said disks through said opening in the casing, all coacting substantially 65 as described and for the purpose specified.

In witness whereof, I have hereunto set my hand and seal in the presence of two witnesses.
